ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA

TWO-STEP SWITCH

Application filed August 30, 1923. Serial No. 660,125.

My invention relates to switches and more particularly to those used in connection with household appliances.

One object of my invention is to provide a switch which may be set in one position and subsequently moved through a series of positions.

Another object of my invention is to provide a switch which is set at one position and which is biased to another position through a plurality of intermediate positions.

Another object of my invention is to provide a switch which is particularly useful in connection with electrical appliances wherein it is desired to employ a switch to perform a plurality of operations automatically in a desired sequence.

In the operation of electrical appliances, particularly electrical ranges, it is often found desirable to set the main controlling switch in such position that a circuit may be closed at a desired time and the circuit through the electrical appliance will continue for a certain period of time, or until the thermal condition of the electrical appliance becomes such as to make it advisable to interrupt the current being supplied thereto. In connection with electrical ranges, this advantage is particularly pronounced when a clock is set to energize the oven at a given time and the current through the oven is interrupted when the oven has reached a given temperature, all these operations being entirely automatic after the setting of the clock and the control switch.

My invention relates to the switch and its details of construction for accomplishing the foregoing objects.

In the accompanying drawings,

Figure 1 is a diagrammatic view of apparatus and circuits embodying my invention.

Fig. 2 is a face view of a switch embodying my invention.

In the preferred embodiment of my invention, an electrical household appliance 1, such as an electric range, having a heating element, is supplied with electrical energy from a supply circuit 2 comprising the conductors 3 and 4, the connection between the circuit 2 and the device 1 being controlled by a switch

5. In addition to the switch 5, a thermostatic switch 6 and a clock (not shown) provided with a pair of relatively movable contact members 7 are associated with the electrical heating appliance 1.

The switch 5 comprises a stationary contact member 8 in electrical connection with the heating appliance 1, and a movable contact member 9, which is connected to the conductor 4 by a conductor 11. The contact member 9 is insulated from an extension 12 which extends in an opposite direction from its point of pivotal support 13. A coil spring 14 surrounds the support 13 and is attached to the movable contact member 9 in such manner as to bias it in a clockwise direction. Stop members 15 and 16 are supplied for the purpose of limiting the movement of the contact member 9.

A pair of latches 17 and 18 are provided for engaging the extension 12. The latches 17 and 18 are controlled by electromagnets 19 and 21, respectively. The coil of the electromagnet 21 is in circuit with the contact members 7 of the time clock, while the coil 75 of the electromagnet 19 is in circuit with the thermostatic switch 6.

As is shown in Fig. 2, the face of the switch is provided with a plurality of indicia which correspond to the several positions of the movable contact member 9, one of which being termed the "set" position, another the "on" position and the third the "off" position. A rotatable handle 22 provided with an indicator 23 is attached to the pivotal support 13 to move the contact member 9 in a counter clockwise direction and thereby wind the spring 14.

In order to operate an electrical heating appliance 1, equipped with my improved switching mechanism, the operator sets the indicator 23 on the switch 5 to the "set" position, which operation places the contact member 9 in position against the stop 15 and places the extension 12 beneath the latch 18 where it is held against the bias of the spring 14. At the same time, the operator sets the clock mechanism for the time at which the relatively movable contact member 7 shall close.

At the proper time, the clock moves the relatively movable contact members into contact to complete the circuit from the conductor 4 through the coil of the electromagnet 21 to the conductor 3. The energization of the electromagnet 21 causes the latch 18 to be withdrawn from the extension 12. The latter, together with the contact member 9, is then turned in a clockwise direction by the spring 14 until the contact members 8 and 9 are in their closed position and the extension 12 engages the latch 17. The electrical heating appliance 1 is then supplied with a current by a circuit which extends from the conductor 4 through the conductor 11, contact members 8 and 9, and heating appliance 1 to the conductor 3. During this operation, the indicator 23 moves to the position indicated by the word "on" on the face of the switch. This circuit persists until the electrical heating appliance 1 reaches a predetermined temperature, whereupon the thermostatic element of the switch 6 expands and closes the circuit extending from the conductor 4 through the thermostatic member 6, and the electromagnet 19 to the conductor 3. Upon the energization of the electromagnet 19 the latch 17 is drawn away from the extension 12, whereupon the spring 14 moves the contact member 9 out of engagement with the stationary contact member 8 and into the "off" position where the contact member 9 rests against the stop member 16. At the same time, the indicator 23 on the switch face moves to the "off" position.

As soon as the temperature of the electrical heating appliance 1 falls to a predetermined value, the thermostatic switch 6 interrupts the circuit through the electromagnet 19, whereupon the entire circuit is de-energized. In order to restore the circuit to the position shown in Fig. 1, it is only necessary to turn the knob 22 so that the indicator 23 points to the "set" position, after which the foregoing cycle of operations may be repeated upon the closing of the clock-controlled contact members 7.

It will thus be seen that I have provided a simple and effective switch for the operation of electrical heating appliances, particularly electrical ranges, which switch may be set in one position and which will thereafter automatically complete a desired cycle of operations.

Although I have described a specific embodiment of my invention, it will be obvious to those skilled in the art that various modifications may be made in the structural parts thereof without departing from the principles set forth. I desire, therefore, to be limited only to the spirit and scope of the appended claims.

I claim as my invention:

1. Switch mechanism comprising a pair of relatively movable contact members, a

switch-operating mechanism therefor comprising a plurality of independent electro-responsive latches, a spring for biasing one of said contact members in one direction, clock-controlled contact members, and a thermo-responsive member, said clock-controlled contact members controlling one of said latches for causing said spring to move one of said contact members so as to engage the other of said contact members and said thermo-responsive element controlling another of said latches for causing said spring to disengage said contact members in accordance with a predetermined thermal condition of said thermo-responsive element.

2. Switch mechanism comprising a stationary contact member, a movable contact member, a spring normally biasing said movable contact member in one direction, and a latching mechanism comprising a plurality of electro-responsive coils and a controlling mechanism for one of said coils comprising a clock mechanism, and a controlling mechanism for another of said coils comprising a thermoresponsive element, whereby said movable contact member is successively released.

In testimony whereof, I have hereunto subscribed my name this 23rd day of August, 1923.

ORA A. COLBY.
